UNITED STATES PATENT OFFICE.

JOHN H. B. REA, OF LA FAYETTE, GEORGIA.

PROTECTED INSULATOR.

No. 909,935.

Specification of Letters Patent. Patented Jan. 19, 1909.

Application filed May 7, 1908. Serial No. 431,409.

To all whom it may concern:

Be it known that I, JOHN H. B. REA, a citizen of the United States, residing at La Fayette, in the county of Walker and State 5 of Georgia, have invented certain new and useful Improvements in Protected Insulators, of which the following is a specification.

My invention relates to insulators and 10 more particularly to the ordinary glass insulator in combination with a protective covering for the same, and the object thereof is to provide a breakable insulator with strong non-breakable protective covering 15 which may be readily and firmly secured thereon.

Further objects and advantages of my present invention will appear in the course 20 of the following description, in which reference is made to the accompanying drawings, forming a part of this specification, in which like numerals are used to designate like parts throughout the several figures, and in which—

25 Figure 1 is a side elevation of my improved protective insulator. Fig. 2 is a central vertical sectional view taken therethrough, and Fig. 3 is a horizontal sectional view taken therethrough on the line 3—3 of 30 Fig. 2.

In the practical embodiment of my invention, I provide a glass or other breakable insulator 1, of the ordinary construction, having a centrally threaded bore for the reception 35 of the ordinary wooden insulator pin 2, and provided with a semi-circular channel 3, in its circumferential face, with a sheet metal casing 4 of the same general shape with the contour of said insulator 1, though 40 of substantially larger size, and having a circumferential depressed channel 5 to aline with the circumferential groove 3, of the insulator.

Between the insulator 1 and its protective casing 4, is poured cement 6, in its plastic state, and the insulator 1 is then worked and turned within said casing 4 to obtain a uniform layer of said cement and to work the same well within its groove 3, and about the depression 5 of the casing 4. 50 When the cement 6 has become thoroughly and evenly distributed between the insulator

and its casing, the same may be placed with their lower circular edges upon a flat surface and left to allow the cement 6 to become 55 hard.

From the foregoing, it will be seen that I am enabled to provide the ordinary insulator of glass or other breakable material, with a strong protective cover which may be readily 60 and firmly secured thereto, and which will withstand shocks that ordinarily break the insulator.

Having fully described my invention, I claim:

1. An insulator of the character described, comprising a breakable insulating body, a metallic casing wholly surrounding the external surface of the same and of the same general shape as the contour of said body 70 portion though of increased dimensions, and a uniformly distributed layer of cementing material interposed between said insulator body and the said casing to firmly lock the same together, substantially as described. 75

2. A protective covering for glass and other breakable insulators, having circumferential wire holding grooves, comprising a metal casing wholly surrounding the external surface of the said insulator, and provided with circumferential depressions to aline with the said wire holding grooves thereof, and a cementing material interposed between said insulator and said casing, and within and about the said grooves 80 and depressions thereof to firmly lock the same together, substantially as described. 85

3. A protective covering for glass and other breakable insulators, comprising a metal casing stamped from a single piece of 90 sheet metal to the general shape of such insulators, to surround the same, and adapted to receive and hold therein a cementing material, prior to the insertion of such insulator, whereby to form a uniform layer of 95 such material, between the insulator and said casing, by movement of said insulator therein, substantially as described.

In testimony whereof I affix my signature in presence of two witnesses.

JOHN H. B. REA.
